UNITED STATES PATENT OFFICE.

LUTHER M. PERKINS, OF ST. LOUIS, MISSOURI.

ELECTRIC CONDUCTOR FOR STREET-RAILWAYS.

SPECIFICATION forming part of Letters Patent No. 435,447, dated September 2, 1890.

Application filed October 17, 1889. Serial No. 327,329. (No model.)

To all whom it may concern:

Be it known that I, LUTHER M. PERKINS, a citizen of the United States, residing at the city of St. Louis, State of Missouri, have invented a certain new and useful Improvement 5 in Electric Conductors for the Motors of Street-Railroad Cars, of which the following is a full, clear, and exact description.

My invention relates to improvements in 10 electric conductors and combined means for transmitting the current therefrom to the motors employed for propelling street-railroad cars, and has for its object to protect underground conducting-wires from the weather 15 and to prevent leaking and grounding of the current.

It consists in features of novelty hereinafter claimed.

In the accompanying drawings, Figure 1 20 represents a longitudinal sectional elevation of a portion of an electric conductor and combined transmitter constructed and arranged according to my invention, and Fig. 2 a plan thereof; Fig. 3, a corresponding view to Fig. 25 1, to an enlarged scale broken away, and Fig. 4 a plan of the same; Fig. 5, a sectional plan, and Fig. 6 a transverse section, taken, respectively, on lines 5 5 and 6 6 in Fig. 3; Fig. 7, a plan of a portion of the conducting-wire; 30 and Fig. 8, a cross-section of the conduit, showing the conducting-wire and contact-plate in position therein.

Like letters of reference denote like parts in all the figures.

35 *a* represents the electric conducting-wire, which is insulated by a covering *b* of some suitable non-conducting material, and laid there-with between longitudinal timbers *c c'*, (or other material,) embedded or fixed along a conduit or other provision therefor (not shown) beneath the ground. Above the timbers *c*, at a suitable distance therefrom, are arranged longitudinal timbers *d*, which are normally maintained parallel to the timbers *c* by intervening rubber tubes *e*, (or springs,) arranged at suitable distances apart, each tube *e* having end flanges, which are secured, respectively, to the timbers *c* and *d* by clamp-plates *f*, or otherwise, so as to effect a perfectly tight 45 joint with the timbers *c* and *d*, and thereby prevent the access of water or dirt to the tubes *e*. Along the upper surface of the tim-

bers *d* are laid flatwise and secured a series of bars or strips *g*, of copper, iron, or other conducting material, having fixed to their under sides the upper ends of rods or wires *h*, of copper or other conducting material, which depend through the timbers *d*, tubes *e*, and timbers *c* to within a short distance of the conducting-wire *a*, a portion *a'* of the latter 55 beneath each rod *h* being denuded of its insulating covering *b*, and thereby exposed, as shown in Fig. 3. The bars or strips *g* are of any suitable length and shaped diagonally at the ends, a short space or clearance being left 60 between the adjacent ends of succeeding bars *g*. Owing to the variations of temperature, and the consequent elongation and shortening of the conducting-wire *a*, the exposed portions *a'* of the conducting-wire *a* are liable to 65 become displaced from beneath the rods *h*, which are at fixed points throughout the bed-timbers, and in order to prevent such displacement I form a series of bends *a''*, Fig. 7, at suitable intervals in the conducting-wire 70 *a*, whereby its expansion and contraction, instead of being cumulative throughout its entire length, is divided up among the respective lengths between the bends *a''*.

In operation the trolley or contact-roller *i*, 75 from which the electric current derived from the conductor passes to the propelling mechanism of the car, as in the case of an overhead wire, rides on the bars or strips *g*, passing from one to the other successively, and in so doing depresses the timber *d* beneath the 80 tread of the roller *i*, as indicated by dotted lines in Fig. 3, thus lowering and causing each rod *h* successively to make contact with the correspondingly-exposed portion *a'* of the conducting-wire *a*, and at the same time compressing each rubber tube *e* until on the passage of the roller *i* beyond a rod *h* the timber *d* is returned to its normal level by the recoil 85 of the compressed tube *e*, (or springs,) and the contact thereby broken between the said rod and the conducting-wire *a*. By this arrangement the electric current is only transmitted from the conducting-wire *a* to the roller *i* through each bar or strip *g* independently 90 and successively during the transit of the roller *i*; but as the latter in passing from one bar to the next across the intervening space remains in contact with both bars the current 95 100

is thereby rendered continuous from the roller *i* to the motor of the car.

By this invention the conducting-wire *a*, being insulated and confined between the longitudinal timbers *c c'*, is effectually protected from weather and leakage of the current therefrom prevented. Furthermore, as the current can only pass from the conducting-wire *a* during the passage of the trolley or roller *i* along any two of the bars or strips *g*, when these are depressed grounding of the current is practically prevented.

I claim as my invention—

1. In an electric railway, a trolley-track having a continuous and yielding bed-timber for the contact-rail, a series of sections of contact-rail mounted thereon, each section provided with a projecting contact-post, and an insulated continuous electric conductor having the insulation removed at intervals, whereby the contact-post can be brought in electrical contact with the conductor when the trolley-track is depressed, substantially as and for the purposes described.
2. In an electric railway, a trolley-track having a continuous and yielding bed-timber

for the contact-rail, a contact-rail mounted thereon, said rail consisting of a series of separate bars or strips of conducting material having diagonally-cut ends and provided with contact-posts, and an insulated continuous electric conductor having the insulation removed at intervals, whereby electrical connection will be established with the contact-rail when the rail is depressed, substantially as and for the purposes described.

3. The combination, with an insulated electrical conductor having the insulation removed at intervals, of spring contact-posts adapted to make contact with the exposed portions of the conductor, said conductor having expansion and contraction loops or bends at intervals throughout its length, substantially as and for the purposes described.

In testimony whereof I affix my signature, in presence of two witnesses, this 11th day of October, 1889.

LUTHER M. PERKINS.
